DESIGN FOR A CONTAINER CAP

Georges Wilmet, Roslyn, N. Y., assignor to Armstrong Cork Company, Lancaster, Pa., a corporation of Pennsylvania

Application April 29, 1938, Serial No. 76,851

Term of patent 3½ years

To all whom it may concern:

Be it known that I, Georges Wilmet, a citizen of Belgium, residing in Roslyn, county of Nassau, and State of New York, have invented a new, original, and ornamental Design for Container Caps, of which the following is a specification, reference being had to the accompanying drawing, forming a part thereof, in which

I claim:

The ornamental design for a container cap, substantially as shown.

GEORGES WILMET.
